ADOLPH LANGSNER, OF CHICAGO, ILLINOIS, ASSIGNOR TO EUGENE DIETZGEN COMPANY, OF CHICAGO, ILLINOIS, A CORPORATION OF DELAWARE

DEVELOPING APPARATUS

Application filed September 8, 1928. Serial No. 304,773.

My invention relates to developing apparatus for light sensitive material and particularly to apparatus for developing light sensitive sheets or continuous strips of paper or the like by the action of a gas, such as ammonia or water vapor, or any other developing gaseous agent.

One of the objects of my present invention is to provide a compact and conveniently operated apparatus for developing sheets or continuous strips of light sensitive material by the action of a developing gaseous medium contained within the apparatus, wherein the arrangement is such that a single operator standing at one point with respect to the apparatus is enabled to feed into the machine either sheets or continuous strips of the material and is enabled to receive the developed sheets or strips as they pass through the machine and are discharged therefrom, the construction being such that the developing medium within the cabinet is prevented from escaping either through the inlet or outlet of the apparatus thereby preventing the developing gases from reaching the operator.

Another object of my invention is to provide a compact and conveniently arranged apparatus for developing sheets or continuous strips of light sensitive material by the action of developing gas enclosed within the apparatus wherein the cabinet is constructed of such convenient height so that it may be provided with an infeeding aperture for permitting an operator to feed the light sensitive material into the machine on one point and wherein the cabinet is provided with a discharge aperture or station located at the top of the cabinet which latter station is substantially head high with the top of the operator when located in operating position with respect to the cabinet and wherein an exhaust dome or suction conduit is disposed immediately adjacent and over the discharge station so as to pull or draw away the occluded gases which are discharged with the developed paper at the discharge station, the location of the discharge station being at head height of the operator which provides for the upward rise of the occluded gases into

the exhauster without coming into contact with the operator so that he is not compelled to breathe in these escaping gases.

Yet another object of my invention resides in providing a developing apparatus of the character above described wherein the material to be developed is passed continuously through the machine in the shortest practicable route, and in a minimum of time for its complete development and is deliverable at the same side of the machine into which it was fed, whereby a single operator can take care of both the infeed and outfeed of the material.

Still another object of my invention resides in the particular arrangement of the driving means or specifically the driving belts within the apparatus for feeding the light sensitive material thereto, therethrough, and therefrom, and in the relation of the means for preventing the escape of the developing gaseous medium through the infeed and outfeed ports of the apparatus.

Yet another object of my invention resides in the provision of a non-corrosive lining for the developing apparatus whereby the developing gases, such as ammonia gas, are completely isolated from the wooden cabinet which forms the developing apparatus. An ancillary object of this feature of my invention resides in the means for interconnecting the sheets of metallic lining material whereby to prevent the passage of the gases by or past the joints formed in the lining material.

Yet another object of my invention resides in the general and particular arrangement of strips for the belt feeding rolls for the light sensitive material which are located at the outlet ports whereby the light sensitive material, as it passes through the discharge port, is required to pass between the rolls and is prevented from being diverted into other paths.

Still another feature of my invention resides in the provision of a discharge roll receiving trough located opposite the discharge port and the provision of a hood immediately thereover for carrying the occluded gases which are on the discharged

95
100

end of the developed paper whereby to prevent their disseminance into the atmosphere. An ancillary object of this feature of my invention resides in the modified construction whereby the exhauster is connected directly to an isolated compartment formed at the discharge aperture whereby to draw away the occluded gases from the developed paper as it passes through the discharge port.

10 Another object of my invention resides in the provision of the driving means for regulating the speed of movement of the small belts or cords constituting the feeding means for the light sensitive material.

15 These and other objects of my invention will be apparent from a perusal of the following specification when taken in connection with the accompanying drawings, wherein:

20 Figure 1 is a side sectional view of my improved apparatus;

Figure 2 is a front view thereof;

Figure 3 is a detail sectional view of the discharge opening showing the stripping members in position;

25 Figure 4 is a top plan view of Figure 3;

Figure 5 is a modified construction of the discharge opening; and

Figure 6 is a modification of the structure shown in Figure 5.

30 Referring now to the drawings in detail, my improved invention consists of a self-contained or practically air-tight or gas-tight cabinet adapted to contain a quantity of developing material in a gaseous state. This developing material may be either steam, water vapor, ammonia gas, or a combination of ammonia gas and water vapor or in fact any other gaseous medium for the development of the light sensitive material. In the 35 present instance, the specific embodiment of the invention is illustrated as adapted to contain a quantity of ammonia gas. As shown in the drawing, the cabinet is supported on suitable legs 2 so that the top of the cabinet 40 stands at a suitable height which is in convenient reach to an operator and so that the flat top of the cabinet may be utilized as a desk, table, or the like. The cabinet is formed with preferably wood top, bottom, side and 45 end members and is preferably of rectangular form.

50 One of the particular features of my invention resides in providing the cabinet with an inner lining of a suitable material which 55 is not effected by the corrosive action of the developing gas, particularly when ammonia gas is used as a source of developing medium. In the preferred form, my cabinet is formed of wooden members but likewise may be 60 formed of sheet metal or any other material. So also in the present instance, the cabinet is preferably lined with sheet metal such as sheet lead or aluminum which is not affected by ammonia or ammonia fumes. The lining or sheet 65 metal 6 as applied to the inner faces of the

wooden cabinet members is formed in a sort of a flexible manner so that the junctions of the angularly disposed members of the cabinet will make closed contact in order that the gases or steam not only cannot escape but also 70 cannot contact with the wood and injure it. In other words, my improved lining construction has a two-fold function: first, to prevent the contact of the injurious gases or steam with the wooden or other members of the cabinet; and secondly, the joints are so arranged and gasketed so as to prevent the escape of the gases and steam past the joints. 75

To this end, the joints of the metal lining are preferably formed as shown in Figure 3 80 of the drawings wherein one of the sheet liners 6 is joined to another of the sheet liners 8 in such a manner to preclude contact of the gas with the wood. In this construction one of the partition members 4 is grooved 85 or recessed and this groove is filled with a yieldable gasket 10 of rubber or other suitable non-corrosive material which groove or recess extends the entire width or length of the particular cabinet member and the lining member lies in this groove and then the yieldable rubber gasket overlies the portion 90 of the lining members which lies in the recess. The area of the rubber gasket is larger than the area of the groove so that when the rubber is laid in the groove a portion of it will 95 project beyond the face of the cabinet member and its lining and will firmly press against the opposite lined face of the co-operating cabinet member and since this 100 yieldable junction extends throughout the length of the two contacting cabinet members the flexible joint thus formed will compensate for any inaccurateness in the joint pieces 105 and will effectively prevent the escape of the gases or steam through the junction. It will also be apparent that by reason of this construction the gases cannot attack the wood due to the lining member. It is evident that 110 these recesses or grooves may be of any particular shape or conformation and may be located not only in the flat face of a wooden partition member but also in the end of the member to form a gas-tight joint. In this manner of making a joint, for a developing 115 chamber of the character indicated, the steam or gas and water vapor and particularly ammonia gas will not have direct access to the wood of the case since if it did have such access the wood would warp and the pores of the wooden parts would absorb the moisture and crack, thereby permitting the escape of the obnoxious gases to the atmosphere outside of the cabinet.

120 The foregoing construction readily lends itself to developing cabinets made of metal since the grooves may be formed directly in the metal and the rubber gaskets inserted directly in these formed recesses.

125 In my present invention I have particu-

larly formed my improved cabinet so that a single operator standing at a predetermined station with relation to one part of the machine may easily take care of the machine, feeding in the continuous strips, or separate sheets if desired, of light sensitive material, and receiving the developed sheet from the discharge point of the machine after the material has passed through the developing chamber. To accomplish this end, I provide a construction wherein the light sensitive material is preferably fed into the machine at the front or one of the sides of the same and is thence fed through the cabinet which contains the developing gas in the shortest possible path which will produce the desired developing effect and the material is then automatically discharged at the outfeed station of the cabinet which is located at the same zone or station at which the infeed is located. In the particular embodiment illustrated, I provide the front of the machine preferably at the lower portion thereof with a transversely extending infeed opening or slot 12 for receiving the light sensitive material to be developed. Opposite this slot, I provide the exterior of the machine with a shelf or support 14 on the under side of which depends a bracket 16 carrying a roller 18 for holding a continuous roll or sheet of light sensitive material 20. In lieu of this, separate sheets of light sensitive material may be placed on the shelf or feeding through the slot 12, if desired. Opposite the slot 12, I provide a single compartment 22 formed by a vertically disposed partition 24 and a horizontally disposed partition 26 which partition extends across the front of the machine co-extensive with its width. Inside of this compartment 22 I provide two spaced apart rollers 28 and 30 which are provided with a series of spaced apart grooves for receiving a plurality of relatively small belts or cords 32 and 34. I also provide a guiding ledge 36 which lies flush with the upper surface of the shelf 14 and projects inwardly to the right of the rolls so that the inner end of this guide 36 overlies the lower roll 28. I also provide a rubber, felt, or partition of other material 38 which extends from the front wall 4 of the cabinet to the roll 30. Partition 24 is provided with an opening 40 for the passage of the belts or cords 32 and 34 and with rubber or felt gaskets 42 which permit the passage of the cords or belts but prevent the escape of the gases through the opening 40. In a similar manner, the horizontal partition 26 is provided with two openings 44 and 46 for the passage of the belts and cords which pass around the roller 30. These openings 42 and 46 are likewise provided with felt or rubber gasket strips.

About midway the height of the cabinet and located at the rear or on the other side of the cabinet, I provide a drum or roll 48

mounted on a shaft 50, one outer end of which projects through the side wall of the cabinet and is provided with a pulley 52 having variant diameters and forming one member of a change speed gearing. A belt 54 runs over this pulley and is adapted to be driven by another smaller pulley 56 mounted on a shaft 58 carrying a worm wheel 60 meshing with a worm 62 on a shaft 64 and an electric motor 66 in turn mounted on a bracket 68 on the exterior of the cabinet. In this manner, I provide a simple, direct driving means of variant speed transmission between the motor and the relatively large roll or drum 52. In addition, I provide a rear portion of the cabinet with a plurality of guide rolls 70, 72, 74 and I provide the front upper portion of the machine with another pair of guide rolls 76 and 78. These two latter rolls are mounted directly opposite the discharge opening or slot 80 located in the front panel of the developing cabinet.

The two sets of endless cords or belts 32 and 34 cooperate with these various rollers and with the openings in the partition members and cabinet members so as to feed either continuous sheets or separate sheets of light sensitive material directly through the cabinet in a minimum of time during which time the sheets are subjected to the action of the developing gas or medium so as to cause the development of the light sensitive material. Referring now to the lower belts or sets of cords 34, it will be seen that the same pass around the roller 28, thence relatively upwardly and around the upper roll 30, thence through the guide slot 44, thence around a separate roller 82, thence across and at an inclined manner upwardly to the rear of the machine hence they pass around the relatively large developing drum 48 and thence forwardly and still upwardly to the front of the machine where they pass around the upper guide roll 76, thence rearwardly around the roll 72, thence downwardly around the roll 70, thence forwardly and downwardly and through the slot 40 in the partition 24, thence around roll 28 against, completing a continuous circuit. In a similar manner, the belts or cords 32 pass around the guide roll 30, thence upwardly through the slot 44 and partition 26, thence around roll 82 and rearwardly and upwardly together with the cords 34 around the developing drum 48, thence forwardly around the front and upper guide roll 78, thence downwardly directly through the slots 46 in the partition 26 to the guide roll 30, again also completing a continuous circuit. It will be noted that the two belts travel together from the lower guide rolls 28 and 30 and the large developing roll 48 to the upper discharge rolls 76 and 78 but at this point the two belts separate, each one returning by a different path to its original starting point so that as these belts lie in spaced apart and

distinct grooves in the various rolls, any light sensitive material in sheets or continuous strip form that is fed onto the shelf 14 and onto the guide ledge 36 and projected into the plane of the belts opposite the opening 12 such material will be carried by the opposed belts through the relatively short path upwardly around the roll 82, thence upwardly in an inclined direction to the rear of the machine around drum 48, thence forwardly and discharged by the discharge rollers 76 and 78, preferably as shown in Figure 1, into a receiving trough 84 which receiving trough is located immediately beneath the exhausting hood 86 which is adapted to remove any occluded gases which may be in the developed material or which may possibly escape through the discharge opening. It will be understood that this hood extends the entire width of the front and lies immediately over the receiving trough 84.

The tension on the belts is preserved by means of the tension roller 74 which runs on roller bearings and is carried by arms 86 which in turn are pivoted upon plates 88 so as to take up the slack in the strings. In other words, the weight of the ball bearing rollers 74 pivotally and freely lying on the two pairs of cords or belts 32 and 34 automatically takes up the slack in these cords while still permitting the free passage of the light sensitive paper therebetween as it passes through the short quick route through the developing chamber. It will be observed that by providing the front and rear surfaces 88 and 90 of the cabinet as glass partitions, the progress of the developing may be observed at all times and if desired, these panels may be made hinged and detachable so as to give free access to the inner portions of the developing chamber.

In order to provide a suitable source of developing medium, I provide at the base of the machine, spaced apart guides 92 which are in the form of shelves adapted to support developing pans or trays 94 and 96 adapted to contain suitable developing solution such as water or liquid ammonia which is heated in any suitable manner as for instance by means of an electric heater, if desired. These pans are preferably filled from the exterior of the cabinet by means of suitable flexible hoses or pipes which have filling nozzles on the outside of the cabinet wall. If desired, the foremost pan, that is, the pan nearer the entrance chamber, may contain water so as to give off water vapor or steam and if desired, the second pan may contain ammonia so that the light sensitive paper is first subjected to a steaming effect to accelerate the developing action and then is carried into the zone of ammonia fumes arising from the pan. The heating of the fluid in these pans is controlled by a suitable thermostat so that a relatively hot gaseous de-

veloping medium may be provided within the developing chamber. This, of course, accelerates the developing action and is particularly adaptable for use where the first pan contains water to give off steam and the second pan contains ammonia to give off hot ammonia gas.

Means is provided at the discharge mouth of the cabinet for stripping the sheets or continuous strips of light sensitive material from the cords and preventing them from following the cords as the cords pass around the rolls. This construction is illustrated clearly in Figures 3 and 4 of the drawings wherein I provide a pair of preferably sheet metal prongs or stripping fingers which are preferably fastened to the under sides of the slot 80 in the front panel 4. These stripping fingers 98 and 100 have their inner portions formed as tongues 102 so as to lie in relatively wide peripheral grooves 104 formed in the rollers 76 and 78. These grooves alternate with the grooves 106 into which the cords or belts 32 and 34 lie. In addition, I provide a flexible gasket of felt or rubber shown at 108 in Figure 3 of the drawings, which is held in place by means of a block 110. This finger lies across the discharge slot 80 in a manner so as to permit the out-feed of the developed material while preventing the escape of the gas therethrough.

As an alternative construction to that shown in Figures 1 and 3 of the drawings, I provide the modified construction of the upper front portion, shown in Figure 5, whereat an isolated discharge chamber is formed by means of a horizontal partition 112 and a vertical partition 114, which partitions with the front and upper walls 4 of the cabinet provide an isolated chamber, one wall of which is provided with a plurality of perforations 116 which connect with an exhaust for sucking the air out of the compartment 118. In this compartment, I mount the rolls 120 and 122 which likewise are grooved and around which the belts 32 and 34 are adapted to pass. The partition 114 is provided with slots 123 for the passage of the belts while the partition 112 is likewise provided with a slot 124 for the passage of the lower cord or belt 32. These openings are suitably packed or gasketed with felt or rubber as hereinbefore described so that the chamber 118 is substantially isolated from the developing chamber. In like manner, this chamber 118 is provided with a discharge slot 126 and is provided with stripping fingers 128 and 130 as hereinbefore described, and in addition is provided with a flexible gasket 132 and a shelf 134 so that light sensitive material carried by the belts will pass through the opening 120 between the discharge rolls 120 and 122. From this point, the light sensitive material is fed out through the discharge slot 126 past the yieldable gasket 132.

Since this chamber 118 is completely cut off from the developing chamber, the light sensitive material discharged may be discharged thereinto without any possibility of developing gas reaching the exterior of the machine.

In Figure 6, I have shown still another modified form of this portion of my invention wherein the two guide rolls 136 and 138 over which the cords 32 and 34 pass are located also in a separate chamber formed by a horizontal partition 140 and a substantially vertical partition 142, thus forming a chamber which is provided with an exhaust conduit or hole 144 connecting with an exhaust pipe 146. The cords 32 and 34 feeding together pass through a slot 148 so that the light sensitive material carried thereby is discharged from between the rolls 136 and 138 into the separate chamber 150 which as shown is closed and the paper is then discharged into this chamber in the form of separate sheets or a continuous roll 160. The front wall 162 of this chamber is formed at a door hinged at 164 so that in an open position, it moves to a downward dotted-line position to form a shelf. When closed, this door 162 forms a closed chamber 150 which is at all times connected with an exhauster 144 so that the light sensitive material fed into this compartment is at all times under the suction of the exhauster so that the occluded gases remaining on the paper will be withdrawn therefrom. In like manner, any gas which may escape from the developing chamber through the slot 148 is likewise taken care of. It will be understood that the partitions 140 and 142 are provided with a sufficient number of slots for the passage of belts therethrough as hereinbefore described and also provided with felt gaskets and packed as hereinbefore described.

It will thus be seen that I have provided a very simple, compact, efficient and economical type of developing cabinet which may be cared for by a single operator and wherein the developed material such for instance as paper, is passed through the machine in the shortest possible route so as to give the maximum time for developing while at the same time during the passage, material is carried by the spaced apart open strands of the belts or cords in a path directly over the rising developing gaseous medium upon the pans. It is automatically discharged without the interposition of the operator. All the operator has to do is to feed in the material at the front basal portion of the machine and to receive it at the upper front portion of the machine, which stations are all within his reach. It will also be seen that the drive is accomplished by driving the relatively large drum 48 so as to drive the two separate sets of belts or strings. This drive may be suitably controlled by varying the ratio of the driving pulleys. It will, of

course, be understood that wherever the shaft of the driving pulley projects from the casing the same is provided with suitable packing or gaskets to prevent the escape of the gases.

It will also be apparent that by reason of constructing my improved developing cabinet so that the top is substantially the height of the head of the standing operator, the top of the cabinet may be used as a support or shelf for various articles while at the same time the location of the discharge station or aperture at the top of the cabinet substantially at head height of the operator permits the discharge of occluded gases at this height from the ground so that in discharging, they will rise and pass above the head of the operator directly into the suction exhauster thereby preventing the injurious effects of the gases reaching the operator.

Another factor of the construction illustrated resides in disposing this discharge aperture at the same side of the cabinet as the infeed station whereby a single operator at this point may take care of both the infeed and the outfeed of the single developing machine.

In connection with the feature of my invention illustrated more clearly in Figure 3 of the drawings, which shows the non-corrosive liner covering for the inner surface of the wood of the cabinet, it is of course to be understood that this thin non-corrosive lining member may be made of any material such as aluminum, Monel, lead or any other non-corrosive metal or may be made of a non-metallic material. In some instances, I may also provide the inner lining of non-corrosive material composed of celluloid or any other similar plastic material or metal. I may also spray the inner face of the wood of the cabinet with non-corrosive substances which will provide a thickness approximately as thick as lead or aluminum sheets, for protecting the wood against the action of the ammonia gas or vapor or steam or other gas. In some instances, I may use celluloid, casein or any other similar substance which will cover the entire surface and stick or adhere to the wood. In connection with the formation of the grooves in the wooden partition members of the cabinet, it will be pointed out that they hold the rubber or other yieldable packing in place and afford means for sealing the joints irrespective of whether the yieldable packing is positioned on a flat board or frame or whether it is inserted on the edge. So also, it will be apparent that by carrying the metal lining or covering through into the grooves and over the surface of the border casing with which the rubber comes in contact provides a further protection to any portion of the wood against the attack of the ammonia, the ammonia fumes, or steam or vapor. Rubber is par-

ticularly adaptable for this function since it is not influenced or changed by ammonia or by any acid used in the developing work.

Having thus described my invention, what I claim as new and desire to secure by Letters Patent is:

1. A developing apparatus of the character indicated comprising members forming an enclosing cabinet, the top of which is relatively low so as to form a flat table-like surface, one wall of the cabinet having an infeed slot for the infeed of light sensitive material and having a discharge opening located at a point on such wall so that a single operator 10 without moving may feed light sensitive material into the inlet and receive the same in fully developed condition from the discharge opening, a plurality of guide rolls within said cabinet, means for rotating certain of said rolls, and a plurality of sets of conveyors disposed around said rolls in endless paths, certain of said rolls comprising a pair lying opposite the infeed slot and certain of said rolls comprising a separate pair lying 20 opposite the discharge slot, said conveyors and rolls being arranged so as to carry the light sensitive material introduced at the inlet slot across the chamber and thence back again to the outlet slot in a continuous path, 30 means in said cabinet for subjecting the traveling light sensitive material carried by the belts to the action of a gaseous developing medium and a lining for the inner surfaces of the cabinet walls, said lining comprising 35 a thin sheet of inert material which is not affected by the action of the gaseous developing medium.

2. A developing apparatus of the character described comprising wooden members 40 forming an enclosing cabinet, said members being lined with sheet material which is not affected by the action of ammonia gas, said lining materials at their junctions being provided with gas-proof joints, an infeed opening 45 for said cabinet and a discharge opening for said cabinet and conveying means in said cabinet constructed and arranged to continuously transport light sensitive material from the inlet opening to the outlet opening and a 50 source of ammonia gas in said cabinet for causing the development of the light sensitive material during its passage therethrough.

3. In a device of the class described, the combination of wooden members forming an 55 enclosing developing cabinet, said members being provided with an inert lining which is not affected by the action of ammonia gas, certain of the wooden members being provided with grooves into which the lining ex- 60 tends, the said grooves being provided with resilient gaskets which are larger than the dimensions of the grooves, whereby said gaskets are pressed against the lining in the grooves to provide a gas-tight joint, means 65 in said cabinet for passing light sensitive ma-

terial from an inlet opening of said cabinet to a discharge opening of the cabinet, a source of ammonia gas in said cabinet, and means for preventing the discharge of the ammonia gas through said inlet or outlet opening.

4. In a device of the class described, the combination of means forming an enclosing cabinet, the upper surface of which is flat and relatively low so as to provide a table surface, one wall of said cabinet having at its lower portion an opening co-extensive with the width of said wall to provide an infeed slot, a pair of guide rolls opposite the infeed slot, the upper portion of said front wall having an outlet opening, a pair of guide rolls 70 opposite said outlet opening and a relatively large developing drum located intermediate the height of the cabinet and adjacent the rear wall of the cabinet, and a plurality of sets of endless conveyors lying in peripheral 75 grooves in said rolls and around said developing drum, said conveyors and rollers being constructed and arranged whereby light sensitive material fed between the pair of rolls opposite the infeed slot is conducted between 80 said belts to the rear of the machine and around said developing drum, and then forwardly to the front of the machine and discharged through said discharge opening, 85 means forming a source of developing gas in said chamber for acting upon the light sensitive material as it is carried along by the belts and means for preventing the escape of said gas through the inlet or outlet opening 90 of the cabinet.

5. In a device of the class described, the combination of means forming an enclosing cabinet, the front wall of which is provided with a horizontal slot co-extensive with the width of the front wall and disposed at the base thereof and provided with a second slot 105 co-extensive with the width of the front wall and lying at the upper portion thereof, a receiving trough disposed on the exterior of the machine and lying opposite the discharge trough, a pair of rollers located opposite the infeed slot and opposite the discharge slot on the inside of the cabinet, a relatively large developing drum disposed at the rear of the cabinet substantially mid-way its height and a plurality of other guide rolls disposed in 110 said cabinet, a plurality of endless conveyors lying in peripheral grooves passing around said developing drum, means providing a source of developing gas lying in said developing chamber and underlying the course or pathway of the conveyors as they pass together from the infeed slot to the discharge slot, and means for preventing the passage 115 of the gases through the infeed and discharge slots.

6. In a device of the class described, the combination of means forming a developing cabinet provided with an infeed slot for the introduction of light sensitive material into 120

- the cabinet, a relatively large developing drum disposed adjacent its rear wall and substantially mid-way its height, said drum having a shaft projecting through the exterior 5 wall of the cabinet, a bracket adjacent said exterior projecting shaft, an electric motor on said bracket, a variable speed driving connection from the end of said motor to the shaft, a plurality of guide rolls in said cabinet, certain of said rolls providing a pair of rolls opposite the infeed slot, in the wall of the cabinet, certain of said rolls providing a pair of rolls opposite the discharge opening formed at the wall of the cabinet, a plurality 10 of sets of endless conveyors passing around said pair of rolls and said developing drum, and arranged so that said conveyors travel together from said pair of rolls around said developing drum to the other pair of rolls, means in said cabinet providing a source of developing gas, and means for driving said conveyors by the rotation of said developing drum. 15
7. In a device of the class described, the combination of means forming a developing cabinet having an infeed slot at the front lower portion thereof and having a discharge opening at the upper portion thereof, an exhauster located adjacent said discharge station so as to withdraw the gases at such point, and feeding means contained within said cabinet and adapted to feed light sensitive material inserted through said infeed slot and convey it through said cabinet and discharge 20 the same at said discharge slot, a source of developing gas within said cabinet adapted to develop light sensitive material during its passage and a lining for the inner surfaces of the cabinet walls, said lining comprising a thin sheet of inert material which is not affected by the action of the developing gas. 25
8. In a device of the class described, the combination of means forming a developing cabinet provided with an infeed slot and a discharge opening, a pair of rollers located at the infeed slot and at the discharge opening, said rollers having spaced apart peripheral grooves, a plurality of other guide rolls including a substantially large developing drum 30 located in said cabinet, a plurality of sets of endless cords passing around said rolls and said developing drum, and lying in said peripheral grooves whereby to provide light sensitive material feeding means and stripping fingers adapted to lie in peripheral grooves in the pair of discharge rolls, said stripping fingers being constructed and arranged to compel the discharge of the light sensitive material outwardly between said discharge rolls. 35
9. In a device of the class described, the combination of means forming a developing cabinet provided with an infeed station and an outfeed station, a pair of rollers located 40 at each station around which pass a plurality of endless conveyors which lie in peripheral grooves in said rolls, said rolls opposite the discharge station having a plurality of relatively wide grooves alternating with the cord grooves and flexible fingers mounted so as to lie in said grooves, and acting as stripping members for directing the light sensitive material outwardly through said rolls to the discharge station. 45
10. A developing apparatus for developing light sensitive material by the action of a gaseous developing medium comprised of wood members forming an enclosing cabinet, a source of gaseous developing medium in said cabinet, means for introducing light sensitive material into said cabinet to be developed therein, the inner walls of said wood being faced with a lining of thin inert material of a character not affected by the action of ammonia gas. 50
11. A developing apparatus for developing light sensitive material by the action of a gaseous developing medium comprised of wall members forming an enclosing cabinet, a source of gaseous developing medium in said cabinet, means for introducing light sensitive material into said cabinet to be developed therein, the wall members having recessed portions at their abutting edges, and a flexible gasket of larger area than said recess compressed in said recess and held therein between adjacent wall members whereby to provide a gas leak-proof joint between said members. 55
12. A developing apparatus for developing light sensitive material by the action of a gaseous developing medium, said cabinet being formed of joined together members, the inner walls of which are lined with a material not affected by the corrosive action of the developing gas within the cabinet, one of the adjacent joined together walls having a superficial recess therein, the inner lining of said wall lying in said recess and a flexible gasket of non-corrosive material lying in said recess and being of larger area than said recess whereby to project beyond said recess and press firmly against the opposite wall of the other joint member whereby to prevent passage of gas past said joint. 60
13. A developing apparatus for light sensitive material comprising a cabinet having an opening for the insertion of light sensitive material into the cabinet, means for creating an atmosphere of a developing medium within the cabinet, an impervious sheathing covering the inner surfaces of the cabinet walls, and means comprising a compressed gasket of resilient material arranged in the seams of the cabinet whereby to prevent the escape of the developing gas therethrough. 65
14. A developing apparatus for light sensitive material comprising a cabinet having an opening for the insertion of light sensitive material into the cabinet, means for creating 70

an atmosphere of a developing medium within the cabinet, an impervious sheathing covering the inner surfaces of the cabinet walls, means comprising a compressed strip of resilient material of circular cross section arranged in grooves of small dimension formed in the abutting edges of the cabinet walls at the seams thereof whereby to prevent the escape of the developing medium through the

10 seams.

15. A developing apparatus for light sensitive material comprising a cabinet having an opening for the insertion of light sensitive material into the cabinet, means for creating an atmosphere of a developing medium within the cabinet, means comprising an impervious sheathing formed and arranged to the inner walls of the cabinet for preventing the developing medium from penetrating the 20 cabinet walls and thus escaping into the atmosphere surrounding the cabinet, said cabinet having grooves formed in the abutting edges of its side walls and a gasket of resilient material compressed into said grooves, 25 the edges of the impervious sheathing extending across and into said grooves.

16. A developing apparatus for light sensitive material comprising a cabinet provided with an aperture for the insertion of light 30 sensitive material into the cabinet, means for creating an atmosphere of a developing medium within the cabinet and means comprising a compressed gasket of resilient material arranged in the seams of the cabinet 35 whereby to prevent the escape of the developing gas therethrough and means comprising an impervious sheathing formed and arranged to the inner walls of the cabinet for preventing the developing medium from penetrating the cabinet walls and thus escaping 40 into the atmosphere surrounding the cabinet.

17. A developing apparatus for light sensitive material comprising a cabinet provided with an aperture for the insertion of light 45 sensitive material into the cabinet, means for creating an atmosphere of a developing medium within the cabinet, means comprising a compressed strip of resilient material of circular cross section arranged in grooves of 50 smaller dimension formed in the abutting edges of the cabinet walls at the seams thereof whereby to prevent the escape of the developing medium through the seams and means comprising an impervious sheathing 55 formed and arranged to the inner walls of the cabinet for preventing the developing medium from penetrating the cabinet walls and thus escaping into the atmosphere surrounding the cabinet, said sheathing extending 60 around the edges of the walls of the cabinet and into said triangular grooves beneath the rubber gasket.

18. A developing apparatus of the character described comprising wooden members 65 forming an enclosing cabinet, said members

being lined with sheet material which is not affected by the action of ammonia gas, said lining materials at their junctions being provided with gas-proof joints, an infeed opening for said cabinet and a discharge opening 70 for said cabinet and conveying means in said cabinet constructed and arranged to continuously transport light sensitive material from the inlet opening to the outlet opening and a source of ammonia gas in said cabinet 75 for causing the development of the light sensitive material during its passage therethrough, and means at the outlet opening for removing from the light sensitive material any ammonia fumes occluded therein during 80 the passage of the material through the developing chamber.

In witness whereof, I have hereunto subscribed my name.
